[57] CLAIM

The ornamental design for a television receiver, as shown and described.

DESCRIPTION

FIG. 1 is a front, top and right side perspective view of a television receiver showing our new design; FIG. 2 is a bottom, rear and right side perspective view thereof; and

FIG. 3 is a front, top and left side perspective view thereto, with a pivotable cover in raised position and an antenna in pivoted and partially extended position.

*Fig. 1**Fig. 2**Fig. 3*
